WILLIAM D. BROOKS, OF BALTIMORE, MARYLAND.

Letters Patent No. 66,208, dated July 2, 1867.

IMPROVED PROCESS OF PRESERVING FRUITS AND OTHER PERISHABLE ARTICLES.

The Schedule referred to in these Letters Patent and making part of the same:

TO ALL WHOM IT MAY CONCERN:

Be it known that I, WILLIAM D. Brooks, of Baltimore, in the county of Baltimore, and State of Maryland, have invented a new and useful improvement in Process for Preserving Fruits, &c.; and I do hereby declare that the following is a full and exact description thereof, reference being had to the accompanying drawings, forming a part of this specification, in which—

Figure 1 is a side elevation, and

Figure 2 a central vertical section of apparatus used in my process.

Similar letters indicate like parts in each of the figures.

The nature of my invention relates to an improvement in the method of expelling air from cans, jars, or other vessels for containing of fresh fruits, or other perishable articles of food, by means of hot sirups or other liquids preparatory to sealing them up hermetically, and also to the use of steam in the operation. Heretofore fresh fruits have been preserved for future use by pouring hot syrup over and upon the same until the liquid had filled all the interstices between the fruit, and the can containing them overflowed. But by this means the air can be but partially expelled from the fruit, &c., so that it has always been found necessary to continue heating the vessel until its contents were partially cooked in order to obtain a preservation thereof, even when subsequently hermetically sealed.

The object of my invention is to expel the air wholly from the fruit or other articles when packed in a can or other vessel, by a flow or current of hot liquid or of steam, or of the two combined, introduced into the can under and beneath its contents, thereby obviating the necessity of a subsequent cooking thereof. I have attained this object by the use of an extended tube containing a column of hot liquid, which, being inserted into the can through its upper open end, shall allow the quantity required in filling the can to flow into the same under strong pressure at or near the bottom thereof, and from beneath its contents, and by the admission of a very fine jet of steam in combination with the liquid. By this means the air is not in any manner confined by the liquid, but is forced out before it so completely as that it is only needed to seal the can after it has been so filled, and the contents of the can are at the same time sufficiently scalded to insure their complete preservation.

To enable others skilled in the art to use this my invention, I will proceed to describe the mode of accomplishing the same.

The fruit or other article is first packed in cans or other vessels so constructed as that they may be readily closed air-tight. These cans are then arranged upon a table or stand, X, so constructed as that it may be readily elevated sufficiently to cause the ends of tubes supplying the preserving syrup and steam to enter the same and penetrate to the bottom thereof. These tubes B are quite small, and so pointed as to pass down readily through the fruit. They each connect with a common reservoir or fountain, C, and are opened and closed by means of suitable cocks a. The reservoir or fountain C is closed and provided with an aperture at the top, which is made large enough to admit of a thorough cleansing of the reservoir through the same. This opening is closed hermetically by a plug, b, screwing into the same, and in which is formed a smaller aperture to receive, when required, a filling-tube. This smaller aperture may be fitted with a cock, or be also closed by a screw-plug c. The fountain or reservoir is heated by an encircling steam or hot-air space or chest, D, formed by an outer jacket or casing, d, extending its entire length to the point at which the supply-tubes B are fitted thereto. Small steam pipes, E, connecting either with the space D or directly with a steam boiler, are carried down each of the supplying tubes B, either within the same or upon the exterior thereof, and terminate each in a very fine jet-aperture at the mouth of the tube. A thermometer, f, may be inserted in the cover of the reservoir to indicate at all times the temperature of its contents. False caps or covers R may be secured upon the supply-tubes B, so that when the tubes are inserted into the cans these covers shall fit down upon the top thereof to prevent loss of heat. The table or stand X, upon which the cans are placed while being thus "processed," may be itself heated or fitted with a hot-water bath, e, in which the cans shall stand until sealed.

The operation of my process is as follows: The syrup, for fruit, or other liquid, for vegetables, &c., to be used, is first poured into the reservoir C at a boiling heat, and the reservoir closed hermetically. Steam or hot air is then introduced into the encircling space D, (I use steam by preference,) and the syrup thereby kept constantly at so high a temperature as to create a strong pressure within the reservoir. When the cans of

fruit, vegetables, or other articles are properly filled and arranged upon the stand X beneath the supply-tubes, as shown in fig. 2, the stand is elevated by means of a treadle or other mechanism until the supply-tubes B severally reach a point very near the bottom of each can, and the false caps R cover the openings in the top thereof, as illustrated by red lines, fig. 2. The cocks a of the supply-tubes are then opened, and at once a current of the hot sirup, or liquid contained under strong pressure in the reservoir C, flows into each can beneath its contents, and, rapidly filling all vacant spaces therein and the cells of the fruit, displaces the air therefrom, forcing it out before it as it flows and fills upward to the top. So soon as the sirup has thus commenced to fill the cans the cocks of the steam-jet pipe E are also opened, and jets of steam at a very high temperature mingling with the sirup, maintain the heat thereof, and prevent it from becoming cooled by contact with the fruit. When the air has thus been displaced from the cans or other vessels, the stand X is allowed to drop down from the tubes B, and the cans are removed and immediately capped and sealed air-tight, and the operation is complete.

I contemplate the use of steam alone in the preservation of tomatoes and other articles containing sufficient fluid in and of themselves, the operation being as above described, but without a flow of liquid, although I prefer to carry the cans up to the tubes upon a movable platform or table under the same, arranged to be elevated by means of a treadle or other suitable mechanism, though I contemplate effecting the same in other ways. After being filled, the cans are to be hermetically sealed in any approved manner, and may be subsequently reheated in a hot-water bath where occasion may require it.

Having thus fully described my invention, I claim as new, and desire to secure by Letters Patent—

Filling cans or other vessels containing fresh fruits or other perishable articles with hot sirup or other fluids, by means of a supply-tube delivering the same under pressure at or near the bottom of the can, substantially in the manner and for the purpose herein set forth.

I claim also the use of steam in the process of preserving fruits and other perishable articles, when delivered into the vessels containing the same substantially in the manner and for the purpose herein set forth.

I claim also the combination of a steam or hot-air space, D, with a reservoir, C, to encircle the same and maintain its contents in a heated state, when said supply pipe is arranged to operate substantially in the manner and for the purpose herein set forth.

WILLIAM D. BROOKS.
